COMBINED CYMBAL MOUNT AND MUFFLER OR SIMILAR ARTICLE

Robert M. Grauso, Bayside, and John J. Morena, Levittown, N.Y., assignors to C. F. Martin & Co., Nazareth, Pa.

Filed Apr. 30, 1971, Ser. No. 139,309

Term of patent 14 years

Int. Cl. D17—04
U.S. Cl. D56—1 E

FIG. 1

FIG. 3

FIG. 1 is a side elevational view of a cymbal mount or similar article, showing our new design, the appearance being the same from all sides.

FIG. 2 is a top plan view; and

FIG. 3 is a bottom plan view thereof.

We claim:

The ornamental design for a combined cymbal mount and muffler or similar article, substantially as shown and described.
